[57] CLAIM

The ornamental design for a Christmas ornament, as shown and described.

DESCRIPTION

FIG. 1 is a front elevational view of a Christmas ornament showing my new design;

FIG. 2 is a right side elevational view thereof the left side elevational view being a mirror image thereof; and FIG. 3 is a bottom plan view thereof, the plan view being a mirror image thereof.

The rear of the ornament bears the peace motif which is visible in FIG. 1 through the thickness of the ornament.
